UNITED STATES PATENT OFFICE.

LAURENCE E. TOPHAM, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

DRIVING AND STOPPING MECHANISM.

Original application filed April 9, 1917, Serial No. 160,751. Divided and this application filed January 17, 1920. Serial No. 352,069.

To all whom it may concern:

Be it known that I, LAURENCE E. TOPHAM, a citizen of the United States, residing at Swampscott, in the county of Essex and State of Massachusetts, have invented certain new and useful Improvements in Driving and Stopping Mechanisms; and I do hereby declare the following to be a full, clear, and exact description of the invention, such as will enable others skilled in the art to which it appertains to make and use the same.

The present invention relates to driving and stopping mechanisms, and more particularly to driving and stopping mechanisms adapted for use in high-speed machines.

The objects of the invention are to improve the construction and mode of operation of driving and stopping mechanisms, and to produce a novel and improved mechanism which will act in a uniform and reliable manner to bring the parts of the machine to rest at a predetermined point in a cycle of operations without undue shock, jar or vibration, and without subjecting the parts to excessive strain.

The invention as illustrated in the present application is embodied in a driving and stopping mechanism comprising high speed driving mechanism for the driven shaft and low speed driving mechanism which is thrown into operation just before the shaft is to be stopped, and an important feature of the invention consists in the provision of mechanism arranged to operate during any rotation of the driven shaft for disconnecting the high speed driving mechanism from the shaft and for connecting the low speed driving mechanism with the shaft at a predetermined point in the rotation of the shaft. This feature insures greater certainty and reliability in the operation of the stopping devices and results in uniform conditions when the low speed mechanism is connected with the shaft so that the stopping devices will act uniformly during each operation thereof.

The invention also comprises various other novel and improved features set forth in the following description and particularly pointed out in the claims, the advantages secured by which will be readily un-

derstood and appreciated by those skilled in the art.

The invention as illustrated in the present application is embodied in a driving and stopping mechanism designed to be applied to an automatic shoe machine such as that illustrated and described in applicant's pending application, Ser. No. 160,751, filed April 9, 1917, of which the present application constitutes a division. It is to be understood, however, that the invention is not limited in its application to any particular class or type of machines but that it may be applied with advantage to various machines.

In the drawings Figure 1 is a view in vertical section of a machine embodying the invention, the section being taken substantially on line 1—1 of Fig. 3; Fig. 2 is a view in horizontal section, taken substantially on the line 2—2 of Fig. 3; Fig. 3 is a view in front elevation, partly broken away and partly in section; Fig. 4 is a detail view in front elevation illustrating certain parts of the stopping mechanism; Fig. 5 is a plan view of the mechanism illustrated in Fig. 4; Fig. 6 is a detail view in rear elevation illustrating certain parts of the stopping mechanism; Fig. 7 is a sectional view taken substantially on the line 7—7 of Fig. 6; Fig. 8 is a detail view in front elevation, partly in section, illustrating certain parts of the stopping mechanism; Fig. 9 is a sectional view taken substantially on the line 9—9 of Fig. 8, and Figs. 10 and 11 are detail sectional views in side and front elevation illustrating particularly the lock bolt carrier and the cooperating cam actuated arm of the stopping mechanism.

The driving mechanism illustrated in the drawing comprises a driving shaft 6 upon which is fixed a disk 8 carrying a driving member 10 of a friction clutch. The driven member 12 of the clutch is carried by a flange extending outwardly from a sleeve 14 loosely mounted upon the driving shaft 6. The sleeve 14 also carries a spiral gear 16 meshing with a spiral gear 18 formed on a sleeve 20 that is mounted on the driven shaft 22 to rotate therewith. While the members 10 and 12 of the main friction driving clutch are engaged, the shaft 22 is driven

2

through the spiral gears 16 and 18 at a speed depending upon the speed of the driving shaft 6. In stopping the rotation of the shaft 22 the members 10 and 12 of the main driving clutch are disengaged and the shaft 22 is stopped through the action of automatically acting devices. The mechanism for stopping the shaft comprises a slow-speed friction clutch which is thrown into operation automatically upon the disengagement of the main driving clutch and then acts first as a friction brake to slow down the speed of the shaft 22 to the speed of the driving member of the clutch, and then to drive the shaft 22 in a forward direction at slow speed to stopping position. When the shaft 22 arrives at stopping position the rotation of the shaft is arrested by a friction brake.

20 To enable the members of the main driving clutch to be engaged and disengaged, the sleeve 14 which carries the driven member of the clutch is arranged to slide longitudinally of the shaft 6 upon which it is mounted. The spiral gear 16 is formed with a cylindrical recess, as shown in Fig. 1, the upper face of which is engaged by a ball thrust bearing 24 interposed between said face and the upper end of a sleeve 26 forming a bearing for one end of the shaft 6. The sleeve 26 is mounted in a bearing on the frame to slide longitudinally of the shaft and the upper end of the sleeve 26 is formed with a flange 28 which is adapted to engage 30 an inwardly projecting flange 30 on a collar 32 threaded into the recess in the spiral gear 16. The sleeve 26 is moved upwardly by the operator upon starting the machine to actuate the sleeve 14 to engage the members of the main driving clutch, and is automatically moved downwardly upon stopping the machine. During the downward movement of the sleeve 26, the flange 28 on the sleeve engages the flange 30 on the collar 32, and 40 moves the sleeve 14 downwardly to disengage the members of the main driving clutch. The collar 32 provides an adjustable connection between the sleeve 26 and the sleeve 14. To enable the collar to be turned readily 50 to adjust the same in the recess in the spiral gear 16, the collar is formed with a series of openings 34 in which may be inserted any suitable tool for turning the collar. The collar, when adjusted, is held in adjusted 55 position by means of a pin 36 mounted in the spiral gear, the lower end of which is adapted to engage in any one of a series of recesses 38 in the collar. The pin is acted upon by a spring 40 attached to the spiral gear and bearing upon the head of the pin, which holds the lower end of the pin in engagement with the recess in the collar.

60 The mechanism by which the sleeve 26 is actuated to cause the engagement and disengagement of the main driving clutch, 65

comprises a disk 42 carried at one end of, and preferably formed integral with a sleeve 44 mounted in a bearing 46 in the frame of the machine, said disk having a series of teeth 48 meshing with a series of teeth 50 70 formed on the exterior of the sleeve 26. To the opposite end of the sleeve 44 is clamped an arm 52 to the outer end of which is connected, by means of a stud 54, a hollow cylinder 56. Through this cylinder passes a 75 rod 58 pivotally connected at one end by a stud 60 to the arm 62 of a lever 64 keyed to one end of a shaft 66 mounted to turn in the sleeve 44. Surrounding the rod 58 within the cylinder 56 is a coiled spring 68 which 80 at its lower end engages the lower end wall of the cylinder and at its upper end acts against a collar 70 held by a stop nut 72 upon the rod, the collar being arranged to slide in the upper end of the cylinder. This 85 spring furnishes a yielding connection between the arm 52 and the lever 64. Upon the opposite end of the shaft 66 is mounted a lock-bolt carrier 74 formed with a dovetailed guide in which is mounted a dovetailed slide 76. The slide is yielding held in elevated position in the carrier 74 by a coiled spring 78 attached at its upper end to a pin 80 secured in the carrier and at its lower end to a pin 82 secured in the slide. 90 Projecting forwardly from the slide 76 is a stud 84 carrying a roll 86 which engages in an irregularly shaped slot 88 formed in a bracket 90 secured to the frame of the machine. This roll also engages in an irregularly shaped slot 92 formed in an arm 94 100 pivoted upon a stud 96 projecting from a lever 98. The lever 98 is provided with a pivot stud or shaft 100 mounted in bearings in the frame of the machine, and is normally held in elevated position by means of a coiled spring 102 attached at its lower end to a pin projecting from a stud 104 formed integral with the lever 98, and at its upper end to a pin 106 mounted on the frame of the machine. The lever 98 is provided with an operating arm 108 terminating in a handle. In starting the machine, the operator seizes the handle of the operating arm 108 and swings the lever 98 downwardly from the position shown in Fig. 3 to that shown in Fig. 4. The arm 94, through its engagement with the roll 86, depresses the roll and the slide 76 upon which it is carried, the roll moving downwardly through the slot 88 in the bracket 90, which acts as a guide for the roll. The lower end of the carrier 74 will thus be swung to the left, Figs. 3 and 4, in starting the machine, and through the connection between the carrier and the disk 42 the disk will be turned in a direction to elevate the sleeve 26 to engage the members of the main driving clutch. When the sleeve 26 has been 110 elevated by the movement of the carrier 115

120

125

130

sufficiently to engage the members of the clutch, the spring 68 will yield during the continued movement of the carrier, and the members of the clutch will be held yielding in engagement through the action of the spring. In order to retain the members of the main driving clutch in engagement until the sewing of the shoe is completed, a latch 110 is fixed to a stud 112 mounted to turn in a bearing in the lower end of the carrier 74, and is arranged to be engaged with the end of a holding catch 114 fixed to a stud 116 mounted to turn in a bearing in the frame of the machine. The catch is held in acting position by means of a coiled spring 118. As the lower end of the carrier 74 is swung to the left upon starting the machine, the acting end of the catch 114 snaps in front of the end of the latch 110 into position to hold the end of the carrier from moving back to the right. When the carrier is thus latched in position, the handle of the arm 108 is released by the operator, and the lever 98 is elevated by the action of the spring 102 to its initial position. In stopping the rotation of the shaft 22 the latch 110 is thrown out of engagement with the catch 114, allowing the lower end of the carrier to be returned towards its right-hand position. As the carrier is released, the spring 78 elevates the slide 76, and through the engagement of the roll 86 with the edge of the slot 88, the lower end of the carrier is swung back to the right. By this movement of the carrier the sleeve 26 is depressed. There is a certain amount of lost motion between the sleeve 26 and the collar 32, and the movement of the sleeve, caused by the swinging movement of the carrier under the action of the coiled spring 78, is not sufficient to disengage the members of the main driving clutch, which are subsequently disengaged at a predetermined point in the rotation of the shaft 22 by mechanism hereinafter described.

The latch 110 may be thrown out of engagement with the catch 114 automatically to stop the shaft 22 during any rotation of the shaft upon the occurrence of a defect in the operation of the machine in which the driving and stopping mechanism is embodied or upon the completion of the operation performed by the machine or the latch may be disengaged from the catch manually at any time by a manipulation of the catch.

The machine is provided with devices which act when the main driving clutch is disengaged to slow down the speed of the shaft 22, and to cause the shaft to stop in a predetermined position. The mechanism for slowing down and finally stopping the shaft 22 of the machine comprises a slow-speed friction clutch which is disengaged while the machine is driven through the

main driving clutch, and is engaged when the main driving clutch is disengaged. This slow-speed clutch when engaged first acts as a friction brake to slow down the speed of the shaft 22 to the speed of the driving member of the slow-speed clutch, and then as a driving clutch to drive the shaft 22 forward to stopping position. The slow-speed clutch comprises driving and driven friction clutch members 120 and 122 mounted on the shaft 22. The driving member 120 of the clutch is journaled upon a sleeve 124 secured by means of a washer 126 and a bolt 128 to a reduced portion of the shaft 22 to rotate with the shaft. The clutch member 120 is driven by means of a bevel gear 130 meshing with a bevel gear 132 formed on the clutch member. The gear 130 is mounted upon the lower end of a sleeve 134 journaled upon a shaft 136 secured at its upper end in the frame. Mounted upon the upper end of the sleeve 134 is a gear 138 which meshes with a gear 140 formed on the disk 8 which carries the driving member 10 of the main driving clutch. The gears 132 and 130, and 138 and 140, are so proportioned that the clutch member 120 is rotated at slow speed as compared with the speed of rotation of the driving member of the main driving clutch. The driven clutch member 122 of the slow-speed clutch is secured to the sleeve 20 which is mounted upon the shaft 22 to rotate with the shaft, but is movable longitudinally of the shaft to carry the driven member of the clutch into and out of engagement with the driving clutch member. The sleeve is secured to rotate with the shaft by means of a bolt 144 threaded into the sleeve, and engaging in a slot 146 in a flange 148 on the sleeve 124. The clutch members are normally held out of engagement by means of a coiled spring 150 seated at one end in a recess in the flange 148 on the sleeve 124, and at its other end in a recess in the sleeve 20. The movement of the sleeve 20 under the action of the spring is limited by the engagement of the stop nut 152 mounted on the end of the bolt 144 with the flange 148.

The mechanism for controlling the engagement and disengagement of the slow-speed clutch comprises a cam groove 154 formed in the sleeve 20, in which engages a cam roll 156 mounted on the upper end of an arm 158 secured to one end of a shaft 160 mounted to turn in a sleeve 162 engaging in a bearing 164 on the frame of the machine. During the normal operation, or while the main driving clutch of the machine is engaged to drive the machine, the arm 158 is oscillated idly by the cam groove 154 and cam roll 156. When the main driving clutch is disengaged, the carrier 74 is locked to the arm 158 by means of a locking bolt consisting of a projection 166 formed on the upper

end of the slide 76, which is adapted to engage in a recess 168 formed in a lateral projection 170 on the arm 158. When the main driving clutch is engaged, the slide 76 then being held in lowered position, the projection 166 is disengaged from the recess 168. When the latch 110 is disengaged from the catch 114 and the slide 76 is elevated by the action of the coiled spring 78, as the arm 158 reaches a certain point in its oscillating movement, the locking projection 166 engages in the recess 168 to lock the lock-bolt carrier 74 to the arm. The lower end of the carrier is adapted to be engaged by a spring-pressed plunger 172 mounted to slide in a suitable guideway in the bracket 90. The plunger is attached to one end of a rod 174, and is acted upon by a coiled spring 176 surrounding the rod 174 and interposed between the plunger and one end of the guideway in which the plunger is mounted. The movement of the plunger under the action of the coiled spring 176 is limited by the engagement with the end of the bracket 90 of a stop nut 178 threaded on the end of the rod. When the carrier 74 is released, the slide 76 rises and the lower end of the carrier swings to the right under the influence of the spring 78, until, before the roll 86 reaches the upper end of the slot 88 the swinging movement of the carrier is yieldingly limited by its engagement with the plunger 172, the roll finally resting in a recess 180 with which the slot is formed. The upward movement of the slide 76 projects the locking bolt 166 into engagement with the recess 168 in the arm 158 to lock the carrier 74 to said arm. Fig. 3 shows substantially the positions of the parts thus far described at this point in the stopping operation. The locking projection 166 on the slide 76 engages in the recess 168 in the projection 170 on the arm 158 to lock the arm to the carrier 74 when the cam roll 156 is located in the right-hand idle portion of the cam groove 154, as shown in Fig. 3. The continued rotation of the sleeve 20 brings the inclined portion of the cam groove 154 leading from the right-hand idle portion of the groove to the left-hand idle portion of the groove into engagement with the roll 156. Through the cooperative action of the cam roll and the cam groove during the engagement of the roll in this inclined portion of the cam groove, the sleeve 20 is shifted longitudinally of the shaft 22 to the right, Fig. 2, to engage the members of the slow-speed clutch, and the carrier 74 is swung on its axis in a direction to carry the lower end thereof farther to the right from the position shown in Fig. 3. By this movement of the carrier the sleeve 26 is depressed to disengage the members of the main driving clutch. The disengagement of the members of the main clutch and the engagement

of the members of the slow-speed clutch are thus effected at a predetermined point in the rotation of the driven shaft 22. This movement of the carrier occurs against the tension exerted by the spring 176 on the plunger 172, and after the cam roll leaves the inclined portion of the cam groove, and is engaged in the right-hand idle portion thereof, the members of the slow-speed clutch are held in engagement with a pressure depending on the tension of this spring. After the members of the slow-speed clutch are engaged, the driving member of the clutch, which is then rotating at slow speed as compared with that of the driven member of the clutch, will first act upon the driven member as a brake to reduce the speed of said member and of the shaft 22, upon which it is mounted, until these parts are rotating at the speed of the driving member of the clutch. The driving member of the clutch will then act to drive the driven member of the clutch and the shaft 22 in a forward direction to stopping position. As the shaft reaches stopping position, through the cooperative action of the cam groove 154 and the cam roll 156, the carrier 74 is first swung in a direction to carry the lower end thereof to the left, after which the sleeve 20 is moved longitudinally of the shaft 22 to the left to disengage the driven member of the slow-speed clutch from the driving clutch member.

The swinging movement of the carrier 74 thus produced actuates the devices for engaging the brake. The brake-actuating devices comprise a lever 182 mounted on one end of or formed integral with the sleeve 162 and carrying a latch arm 184 secured to a stud 186 mounted in the left arm of the lever, said latch arm being arranged to engage the left side of a projection 188 on a pin 190 projecting forwardly from the slide 76. The stud 186 is acted upon by a spring 192 which tends to swing the latch arm 184 rearwardly into position to be engaged by the pin 190. During the normal operation of the machine, or while the slide 76 is held in lowered position, the pin 190 is located below the latch arm 184. As the slide 76 rises under the influence of the coiled spring 78, upon the release of the carrier 74, to stop the machine, the lower end of the carrier 74 does not swing to the right far enough to carry the pin 190 beyond the end of the latch arm 184, but the pin rises behind the latch arm and engages an inclined face 194 formed on the rear side of the end of the arm. As the lower end of the carrier is swung farther to the right immediately after the engagement of the members of the slow-speed clutch, the movement of the carrier carries the projection 188 on the pin 190 beyond the end of the arm 184, and the arm is then swung rearwardly into position to

engage the left side of the projection. When the lower end of the carrier 74 is swung back to the left, just before the disengagement of the slow-speed clutch, 5 the lever 182 is swung to the left with the carrier through the engagement of the projection 188 with the end of the latch arm 184. This movement of the lever 182 effects the setting of the brake. The central portion 10 or hub of the arm 184 is provided with an abutment face 196 for engagement with an arm 198 carried by a brake actuating ring 200 surrounding the shaft 22. The ring is pivoted upon an eccentric pin 202, 15 and is formed with oppositely projecting lugs 204 which engage in recesses 206 in a brake disk 208 carried by a sleeve 210 mounted on the shaft 22 to slide longitudinally of the shaft but held from rotation with the 20 shaft. The brake disk and the sleeve are held from rotation with the shaft 22 by the engagement of the lugs 204 on the ring 200 in the recesses 206 in the brake disk. The 25 brake disk 208 is provided with a facing of friction material 216 for engagement with a brake surface 218 formed on a disk 220 mounted on the shaft 22. The sleeve 210 is acted upon by a leaf spring 222 interposed between one end of a bearing 224 and 30 a ring or collar 226 threaded upon the end of the sleeve, which spring 222 normally holds the sleeve in position with the brake disk 208 out of engagement with the disk 220. As the lever 182 is swung to the left 35 by the movement of the carrier 74, the abutment face 196 on the latch arm 184 engages the arm 198 on the brake-actuating ring 200, and turns said ring about the eccentric pin 202 upon which it is pivoted, thereby 40 causing the ring to move the brake disk 208 into engagement with the brake surface 218 of the disk 220 to arrest the rotation of the shaft 22. By the adjustment of the eccentric pin 202 upon which the brake-actuating 45 ring is pivoted, the position of said ring may be regulated so as to produce the required action between the members of the brake to stop the rotation of the shaft 22 quickly and efficiently at the predetermined point in the 50 rotation of the shaft.

The operation of the various parts of the mechanism illustrated in the drawings has been indicated in the preceding description but may be briefly summarized as follows:— 55 Starting with the parts in the position illustrated in Fig. 3, in which the shaft 22 and sleeve 20 are at rest, a depression of the handle 108 moves the arm 94 downwardly and through its engagement with the roll 86 of the lock bolt carrier slide depresses the slide and swings the lock bolt carrier into the position illustrated in Fig. 4. The downward movement of the lock bolt slide removes the pin 190 on the slide from engagement with the latch arm 184 and thus

releases the brake disk 208 from engagement with the disk 220 on the shaft 22. The swinging movement of the lock bolt carrier rotates the disk 42 so as to elevate the sleeve 26 and engage the members of the main 70 driving clutch. While the machine is running, the lock bolt carrier is held in the position illustrated in Fig. 4 by the engagement of the catch 114 with the latch 110 on the lock bolt carrier. To stop the machine, 75 the catch 114 is actuated to release the latch 110. At this time, the arm 94 is in its raised position and as soon as the lock bolt carrier is released the lock bolt slide is raised by the action of the spring 78 and the 80 lock bolt carrier is swung in a counter clockwise direction until its lower end engages the plunger 172. This movement of the lock bolt carrier is not sufficient to disengage the members of the main driving clutch. 85 While the machine is running the arm 158 is being oscillated idly by the timing cam groove 154. After the lock bolt slide is raised by the spring 78, the lock bolt is engaged by the arm 158 and during the continued oscillation of the arm the lock bolt carrier is swung still further in a counter clockwise direction so as to disengage the main driving clutch members. Continued 90 rotation of the sleeve 20 carrying the timing cam groove 154 causes the sleeve to be forced toward the right, as indicated in Fig. 3, thereby engaging the members of the slow speed clutch. The slow speed clutch acts as a drag until the speed of the shaft 22 is reduced to that of the driving member of the slow speed clutch. Continued revolution of the sleeve 20 brings the shaft 22 to stopping position, at which point in the revolution the sleeve 20 is moved to the left, as viewed 95 in Fig. 3, to release the members of the slow speed clutch and the lock bolt carrier is swaged slightly in a clockwise direction to apply the brake through the engagement of the pin 190 with the latch arm 184. 100

The nature and object of the invention having thus been explained, and a mechanism embodying the invention in its preferred form having been described, what is claimed is:

1. A driving and stopping mechanism having, in combination, a shaft, high and low speed driving mechanisms therefor, and means for disconnecting the high speed driving mechanism from the shaft and for connecting the low speed driving mechanism with the shaft at a predetermined point in the rotation of the shaft and for thereafter disconnecting the low speed driving mechanism from the shaft. 120

2. A driving and stopping mechanism having, in combination, a shaft, high and low speed driving mechanisms therefor, and means arranged to operate during any rotation of the shaft for disconnecting the high 130

6 speed driving mechanism from the shaft and for connecting the low speed driving mechanism with the shaft at a predetermined point in the rotation of the shaft, and for disconnecting the low speed driving mechanism from the shaft at another predetermined point in the rotation of the shaft.

3. A driving and stopping mechanism having, in combination, a shaft, high and low speed driving mechanisms therefor, means arranged to operate during any rotation of the shaft for disconnecting the high speed driving mechanism from the shaft and for connecting the low speed driving mechanism with the shaft at a predetermined point in the rotation of the shaft and for thereafter disconnecting the low speed driving mechanism from the shaft, and means for stopping the shaft at a predetermined point in its rotary movement when the low speed driving mechanism has been disconnected therefrom.

4. A driving and stopping mechanism having, in combination, a shaft, high and low speed driving mechanisms therefor, and means actuated through the high speed driving mechanism while the shaft is connected therewith for disconnecting the shaft from the high speed driving mechanism and connecting the shaft with the low speed driving mechanism.

5. A driving and stopping mechanism having, in combination, a shaft, high and low speed driving mechanism therefor, means actuated by the driven mechanism for disconnecting the high speed driving mechanism from the shaft and means for connecting the low speed driving mechanism therewith.

40 6. A driving and stopping mechanism having, in combination, a shaft, high and low speed driving mechanism therefor, and means including a timing cam rotating at the same speed as the shaft for disconnecting the shaft from the high speed driving mechanism and connecting the same with the low speed driving mechanism at a predetermined point in any rotation of the shaft.

7. A driving and stopping mechanism having, in combination, a driving shaft, a driven shaft, a high-speed driving clutch for driving the driven shaft from the driving shaft comprising a driving clutch member fixed to the first shaft, a sleeve loose on the first shaft and slidably longitudinally thereof, a driven clutch member mounted on the sleeve, a sleeve fixed to the second shaft and slidably longitudinally thereof, gearing connecting the sleeves, a slow-speed driving clutch comprising a driving clutch member loose on the second shaft, a driven clutch member mounted on the second sleeve, speed-reducing gearing connecting the driving shaft with the slow-speed driving clutch member, means for moving the

first sleeve to engage and disengage the high speed driving clutch, and means for moving the second sleeve to engage the slow-speed clutch upon the disengagement of the high-speed clutch and to disengage the slow-speed clutch.

8. A driving and stopping mechanism having, in combination, a driving shaft, a driven shaft arranged transversely to the driving shaft, a high-speed driving clutch for driving the driven shaft from the driving shaft comprising a driving clutch member fixed to the driving shaft, a sleeve loose on the driving shaft and slidably longitudinally thereof, a driven clutch member mounted on the sleeve, a sleeve fixed to the driven shaft and slidably longitudinally thereof, gearing connecting the sleeves, a slow-speed driving clutch comprising a driving clutch member loose on the second shaft, a driven clutch member mounted on the second sleeve, speed-reducing gearing connecting the driving shaft with the slow-speed driving clutch member, means under control of the operator for moving the first sleeve to engage the high-speed driving clutch to start the machine, and means operated through the high-speed clutch for moving the first sleeve to disengage the high speed clutch and for moving the second sleeve to engage the slow-speed clutch upon the disengagement of the high-speed clutch and operated through the slow speed clutch to disengage the slow speed clutch.

9. A driving and stopping mechanism having, in combination, a driven shaft, a high-speed friction driving clutch for driving the shaft comprising driving and driven clutch members, one of which is mounted for axial movement to engage and disengage the clutch, a slow-speed friction driving clutch comprising driving and driven clutch members, an axially movable sleeve upon which the driven member of the slow speed clutch is mounted, means for moving the sleeve to engage and disengage the slow-speed clutch comprising a cam carried by the sleeve, a lever normally oscillated idly by the cam, a movable lock-bolt carrier, means acting on the carrier to resist movement of the carrier in one direction, a lock bolt movably mounted in the carrier for locking the carrier to the lever to cause axial movements of the sleeve to engage and disengage the slow-speed clutch, means for actuating the lock bolt to lock the carrier to and unlock it from the lever, and means for actuating the axially movable member of the high-speed clutch to engage and disengage the high speed clutch from the movements of the lock-bolt carrier.

10. A driving and stopping mechanism having, in combination, a driven shaft, a high-speed friction driving clutch for driving the shaft comprising driving and driven

- clutch members, one of which is mounted for axial movement to engage and disengage the clutch, a slow-speed friction driving clutch comprising driving and driven 5 clutch members, an axially movable sleeve upon which the driven member of the slow speed clutch is mounted, means for moving the sleeve to engage and disengage the slow-speed clutch comprising a cam carried by 10 the sleeve, a lever normally oscillated idly by the cam, a pivoted lock-bolt carrier, means acting on the carrier to resist movement of the carrier in one direction, a lock bolt movably mounted in the carrier for 15 locking the carrier to the lever to cause axial movements of the sleeve to engage and disengage the slow speed clutch, means for swinging the carrier and projecting and withdrawing the lock bolt to lock the carrier 20 to and unlock it from the lever, and connections for actuating the axially movable member of the high speed clutch to engage and disengage the high speed clutch from the swinging movements of the lock-bolt carrier. 25
11. A machine having, in combination, a high-speed driving clutch, a slow-speed driving clutch, means for engaging and disengaging the high-speed clutch, means for 30 engaging the slow-speed clutch when the high-speed clutch is thrown out, and for disengaging the slow-speed clutch when the shaft reaches stopping position, comprising a sleeve upon which the movable member of 35 the slow speed clutch is mounted, a cam carried by the sleeve, a lever normally oscillated idly by the cam, a movable lock-bolt carrier, a lock bolt movably mounted in the carrier for locking the carrier to the lever 40 to cause the engagement and disengagement of the clutch, a brake, and connections between the lock-bolt carrier and the brake for engaging the brake from the movement of the carrier as the slow-speed clutch is disengaged. 45
12. A driving and stopping mechanism having, in combination, a shaft, a clutch for driving the shaft, a sleeve fixed to the shaft and longitudinally movable thereon and 50 carrying the driven member of the clutch, means for controlling the engagement of the clutch comprising a cam carried by the sleeve, a lever normally oscillated idly by the cam, a pivoted lock bolt carrier, a lock bolt 55 slidably mounted in the carrier to lock the carrier to the lever and thereby effect longitudinal movement of the sleeve on the shaft, and means for controlling the position of the lock bolt. 60
13. A driving and stopping mechanism having, in combination, a shaft, a clutch for driving the shaft, a sleeve fixed to the shaft and longitudinally movable thereon and carrying the driven member of the clutch, means for controlling the engagement of 65 the clutch comprising a cam carried by the sleeve, a lever normally oscillated idly by the cam, a pivoted lock bolt carrier, a lock bolt slidably mounted in the carrier to lock the carrier to the lever and thereby effect 70 longitudinal movement of the sleeve on the shaft, means for controlling the position of the lock bolt, a brake, and means actuated by the movement of the lock bolt carrier for engaging the brake. 75
14. A driving and stopping mechanism having, in combination, a shaft, a clutch for driving the shaft, a sleeve fixed to the shaft and longitudinally movable thereon and carrying the driven member of the clutch, means for controlling the engagement of the clutch comprising a cam carried by the sleeve, a lever normally oscillated idly by the cam, a lock bolt carrier, a lock bolt slidably mounted in the carrier to lock the carrier to the lever and thereby effect longitudinal movement of the sleeve on the shaft, means for controlling the position of the lock bolt, a brake independent of the sleeve, and means for engaging the brake comprising a latch arranged to be moved into operating position during the movement of the carrier in one direction and to be actuated from the carrier during its return movement. 85
15. A driving and stopping mechanism having, in combination, a shaft, driving mechanism for the shaft, means for controlling the connection of the driving mechanism with the shaft comprising a cam, a member normally oscillated idly by the cam, a normally stationary member, a coupling device for connecting said members to render the clutch controlling means active, a brake and means for engaging the brake comprising a latch arranged to be moved into operating position during the movement of the latter member in one direction and to be actuated from the latter member during its return movement. 90
